UNITED STATES PATENT OFFICE.

FREDERICK BLACKBURN, OF PALMYRA, NEW JERSEY, ASSIGNOR, BY MESNE ASSIGNMENTS, TO HIMSELF, FRANKLIN S. HOVEY, OF BEVERLY, NEW JERSEY, AND TIMOTHY MERRICK, OF HOLYOKE, MASSACHUSETTS.

STRAW-BRAID-SEWING MACHINE.

SPECIFICATION forming part of Letters Patent No. 380,167, dated March 27, 1888.

Application filed August 20, 1885. Serial No. 174,858. (No model.)

To all whom it may concern:

Be it known that I, FREDERICK BLACKBURN, a citizen of the United States, residing in Palmyra, Burlington county, New Jersey, have invented certain Improvements in Braid-Guides for Straw-Braid-Sewing Machines, of which the following is a specification.

The object of my invention is to so construct the braid-guides of a straw-braid-sewing machine as to facilitate the proper feeding of the braid, to permit any desired lap of the braid, and to release the braid from the control of the guides when necessary.

In the accompanying drawings, Figure 1 is a side view of part of a straw-braid-sewing machine with my improved braid-guides. Fig. 2 is a sectional plan on the line 1 2, Fig. 1. Fig. 3 is an end view of the machine. Fig. 4 is a transverse section on the line 3 4, Fig. 1; and Fig. 5 is a perspective view of the braid-guides and part of the machine.

The machine shown in the drawings is one of the "Willcox & Gibbs" type, although it should be understood that my invention is not limited to such a machine, the latter being selected simply because it is the one most used for this class of work.

A is the frame of the machine; B, the driving-shaft; D, the needle-bar; D', the needle-arm; E, the presser-bar, and C the rotating hook, all constructed as usual.

The feeding devices of the machine have not been shown, as they form no part of my invention, and may be of any of the usual constructions, although I prefer devices such as shown in my application for patent, filed July 11, 1884, Serial No. 137,414.

P is the guide for the lower layer of braid, and P' the hooked retainer therefor. The lateral adjustment of the guide P is effected by a double-threaded screw, m, similar to that described in my Letters Patent No. 279,855, dated June 19, 1883, one portion of the screw having a right-hand thread adapted to a nut, n, on the guide, Figs. 1 and 2, and the other portion a left-hand thread adapted to a nut, n', so that on turning the screw there is a movement of the guide equal to the combined pitch of the threads. The nut n', instead of being fixed,

however, is carried by a screw-stem, m', adapted to a slot, m², in a bracket, Q, and having a thumb-nut, m³, so that on loosening this nut the guide P may be rapidly retracted to the extent of the length of the slot without manipulating the screw m, and on again restoring the nut to the front end of the slot the guide will be returned to its former position, there being no interference with the adjustment of the guide due to the screw m. This feature is of importance in forming short rows on hats, where it is desirable at times to move the lower braid-guide rapidly out of the way while cross-sewing the laps and to restore it to its former position as soon as this operation is completed.

S is the upper braid-guide carrying the separator-plate S', Fig. 5, this guide being secured to a spindle, p, which can turn and slide in a bearing in a bracket, T, on the frame, and is threaded for adaptation to a nut, p', longitudinally confined to said bearing by a plate, p², so that on turning the nut the stem will be advanced or retracted and the upper guide adjusted. The guide can be readily thrown back out of the way when it is desired to sew together layers without any lap, the spindle p in this case turning in its bearings, and a spring, s, acting upon a plate bearing on a flattened portion of the spindle, as shown in Fig. 4, so as to hold the guide in its elevated position. The lower braid-guide being retracted, the rim of the hat can, when the upper braid-guide is thrown upward, project laterally inward beneath said guide and beyond the needle to any desired extent, so as to permit the sewing of top layers of braid on the brim of the hat at any desired point in the width of the same.

A presser, V, for the upper braid is carried by an arm, V', hung to the stem p and adjustable thereon, so as to adapt the presser to different thicknesses of braid, a set-screw, v, securing the arm in position after adjustment.

I claim as my invention—

1. The combination of the lower braid-guide and its adjusting-screw, a nut receiving said screw and having a projecting stem, a supporting bracket having an elongated slot through which said stem projects, and a retaining-nut on said stem, all substantially as specified.

2. The combination of the needle and work-plate of a sewing-machine with a plate bearing on the lower layer of braid and located at the inner side of the needle, so as to guide the upper 5 layer of braid thereto, and means for pivoting said plate at its outer end, so that it can be thrown back out of the way, all substantially as specified.
3. The combination of the needle and work-plate of a sewing-machine, a laterally-movable edge-guide for the lower layer of braid, an upper edge-guide bearing on the said lower layer and located at the inner side of the needle, and means for pivoting said plate at its outer end, so 10 that it can be thrown back out of the way, all substantially as specified.
4. The combination of the work-plate and needle of the machine, an upper edge-guide having a laterally-projecting stem, and means to 15 enable said stem both to turn and to slide laterally in a bracket on the frame, whereby the guide can be adjusted laterally for different laps of braid, or can be thrown back, so as to permit the brim of a hat to pass beneath it, all 20 substantially as specified.
5. The combination of the bracket T and a spring contained therein with a guide for the inner edge of a strip of braid, said guide being provided with a pivot-stem fitted to a bearing in the bracket and having a flattened portion 25 forming a bearing for the end of the spring, all substantially as specified.
6. The combination of the bracket T, a braid-guide having a threaded stem fitted to an opening in the bracket and free to turn and to slide 30 therein, and a nut adapted to said threaded stem and free to turn with the same, but confined longitudinally to the bracket, all substantially as specified.
7. The combination of the braid-guide having a pivot-stem with the braid-presser having an arm secured to but adjustable circumferentially on said stem, all substantially as specified.

In testimony whereof I have signed my name to this specification in the presence of two sub- 40
scribing witnesses.

FREDERICK BLACKBURN.
